United States Patent Office.

S. N. PARK, OF BLOOMSBURY, NEW JERSEY.

Letters Patent No. 98,186, dated December 21, 1869.

IMPROVEMENT IN RAILWAY-RAIL CHAIRS.

The Schedule referred to in these Letters Patent and making part of the same.

To all whom it may concern:

Be it known that I, S. N. PARK, of Bloomsbury, in the county of Hunterdon, and in the State of New Jersey, have invented certain new and useful Improvements in Railroad-Chairs; and do hereby declare that the following is a full, clear, and exact description thereof, reference being had to the accompanying drawings and to the letters of reference marked thereon, making a part of this specification.

The nature of my invention consists in the construction of a railroad-chair, having, on the inside, four projecting points, which drop down through notches made in the base of the rails, and the chair then secured by an inclined or wedge-shaped false bottom.

In order to enable others, skilled in the art to which my invention appertains, to make and use the same, I will now proceed to describe its construction and operation, referring to the annexed drawings; in which

Figure 1 is an end view of the chair, with the rails inserted,

Figure 2 is a side view of the rails, showing a section of the chair,

Figure 3 is a longitudinal vertical section of the railroad-chair, and

Figure 4 is a bottom view of the rail, showing the notches in its base.

A represents the railroad-chair made of one piece, in such a manner that the rails B B can be inserted, one from each end.

In the roof of the chair A are four projections, *a a*, one on each side, at each end, and when the rails are inserted in the chair, the chair drops down with said projections through notches, *b b*, made in the base of the rail. The chair A then fits snugly on top of the base, and on the sides of the rails B B.

Under the base of the rails, through the chair, is then inserted a false bottom, C, which firmly holds the chair and rails together. The false bottom C is inclined or wedge-shaped, and the bottom of the chair has a corresponding incline, so that the false bottom will present a level surface against the base of the rails.

The false bottom C is locked by a key, D, passed through the same, as seen in fig. 1.

Having thus fully described my invention,

What I claim as new, and desire to secure by Letters Patent, is—

The combination of the chair A, projections *a a*, rails B B, with notches *b b*, false bottom C, and key D, all constructed and arranged substantially as and for the purposes herein set forth.

In testimony that I claim the foregoing, I have hereunto set my hand, this 13th day of October, 1869.

S. N. PARK.
